United States Patent Office.

CHARLES STHORE, OF MONTANO, IOWA, ASSIGNOR TO HIMSELF AND LEVI HEIGUS.

Letters Patent No. 81,554, dated August 25, 1868.

IMPROVEMENT IN MOULDS FOR CASTING SLEIGH-SHOES.

The Schedule referred to in these Letters Patent and making part of the same.

TO ALL WHOM IT MAY CONCERN:

Be it known that I, CHARLES STHORE, of Montano, in the county of Boone, and in the State of Iowa, have invented certain new and useful Improvements in Mould for Moulding Sleigh-Shoes; and do hereby declare that the following is a full, clear, and exact description thereof, reference being had to the accompanying drawings, and the letters of reference marked thereon.

The nature of my invention consists in the construction of a mould for moulding the sole of a sleigh. It consists of a cast-iron box, in the shape of the sled-shoe, with a lid on the top to make it tight, opening with hinges, and with an opening at one end for pouring in the metal, and with steel pins in the box, which are pulled out after the metal is cool, leaving a hole in the shoe.

In the annexed drawings, making a part of this specification, A and B represent the bottom and top pieces of my mould for sleigh-shoes. The bottom piece, A, is bent or curved at the front end, as shown in the drawings, and is grooved out in the middle of the upper side in the form shown in Figure 3.

The rear end of the groove in the bottom A is bevelled toward its under side. The corners of the bottom piece are cut away, forming thin flanges next to the groove in which the shoe is moulded.

The upper part, or lid B, is made in form to correspond and fit on the bottom, A, and is hinged thereto, so as to be readily removed, and yet always fit in the same way and place.

Both the bottom and top are provided with corresponding holes, x x, through which I put bolts so as to have the holes for bolting the shoe to the runners cast in said shoe.

At the front and upper end of the piece A, I make a circular bowl or vessel, d, as is fully shown. Leading from the vessel or receptacle d is a spout or passage, e, directly into the groove in which the shoe is formed.

The lid B is held down by means of catch, hook, and staple.

I ordinarily make my mould of cast iron, but it may be made of any suitable material.

Having thus fully described my invention, what I claim as new, and desire to secure by Letters Patent, is—

The flask or metallic mould for casting sleigh-shoes, constructed and arranged as shown and described.

In testimony that I claim the foregoing, I have hereunto set my hand, this 11th day of February, 1868.

CHARLES STHORE.
